FIG. 5

UNITED STATES PATENT OFFICE

2,663,045

PORTABLE BRUSHING AND NAP-RAISING
ATTACHMENT FOR CARPET CLEANING
MACHINES

Joseph D. Conway, Cleveland Heights, Ohio

Application March 4, 1950, Serial No. 147,603

6 Claims. (Cl. 15—328)

1

The present invention relates to rug and carpet cleaning apparatus, and more particularly, to a power driven apparatus for renovating the nap of pile fabrics such as rugs.

In view of the development of portable scrubbing and lathering machines, much of the rug and carpet cleaning which is now performed takes place on the premises where the carpet lies. Formerly it had been the practice to remove carpets from the floor and send them to commercial establishments to be cleaned. The portable scrubbing machines do a highly satisfactory job of cleaning and obviate the necessity of removing the carpet.

The carpet which is to be cleaned has usually been walked upon for a considerable length of time and dirt and dust have been tread deeply into the carpet. The scrubbing machines can remove most of this dirt, but in view of the flat, matted condition of the pile and deep penetration of the dirt, it is desirable that the carpet receive some preliminary treatment which will serve to raise the dirt closer to the surface so that it can be removed by the scrubbing machine. Such treatment should also remove some of the dirt and should raise the pile or nap of the carpet so that the action of the scrubbing machine will not be nullified by matted threads and fibers. The present invention serves this purpose.

The use of the scrubbing machine on the carpet wets the pile to some extent and this wetting action plus the horizontal mechanical action of the rotary scrubbing brush which is used again causes the pile or nap to flatten. This flattening or matting of the nap will occur most frequently in deep pile carpets where it is most undesirable and spoils the appearance of the carpet. The apparatus of my invention will serve to raise this flattened nap and renew the appearance of the carpet.

Thus, it is a primary object of my invention to provide power-driven apparatus for restoring the nap of carpets to raised condition both before and after the scrubbing operation.

A further object of my invention is to provide apparatus of the character described, which will penetrate the pile of a carpet and raise the ingrained dirt and grit toward the surface where it can be acted upon by a scrubbing machine.

Another object of my invention is to provide apparatus which will brush the nap of a pile fabric into an upright position so that it will be soft and yielding.

Still another object of my invention is to provide apparatus of the character described, which

2

can be power driven by the power unit of the scrubbing apparatus.

A further object of my invention is to provide such apparatus with reversing means so that its operation will be effective whether it be moving forwardly or rearwardly.

Still another object of my invention is to provide apparatus of the character described, which is light-weight, portable, and flexible in operation.

10 Other objects and advantages of the invention will be apparent during the course of the following description.

In the accompanying drawings, forming a part of this specification, and in which like numerals are employed to designate like parts throughout the same,

Fig. 1 is a side elevation of a nap-brushing apparatus embodying the features of my invention, portions thereof being broken away to show 20 details of construction.

Fig. 2 is a bottom plan view of the apparatus shown in Fig. 1, with certain parts removed or broken away to clearly illustrate the invention.

Fig. 3 is a fragmentary cross-sectional view of 25 the splined connecting shaft, taken on line 3—3 of Fig. 2.

Fig. 4 is a plan view of the coupling plate of the apparatus.

Fig. 5 is an elevational view, partially in section, showing the bayonet-type connector which engages the coupling plate of Fig. 4.

Referring more particularly to the drawings, the apparatus is seen to comprise a housing 1 having a top 2, oppositely disposed sides 3 and 4, 35 and an arcuate closed end portion 5, which forms the rear of the housing.

A closed chamber 6 is formed in the housing 1 by means of an L-shaped partition 7 which is secured to the housing as by welding. The 40 partition has a horizontally extending portion 8 forming a bottom and has a vertically extending side portion 9 which may be secured, for purposes of reinforcement, to a transverse piece of angle iron 10 which is welded to the underside of the top 2 of the housing.

A conventional form of motor driven exhaust blower 11 is mounted on the top 2 of the housing and extends into the chamber 6 through an opening 12 which is provided therefor in the top 2. The blower is equipped with a cloth dust collector or filter 13 for a purpose to be more fully described hereinafter.

The portion of the housing 1 which lies forward of the chamber 6 is open at the bottom and in this forward portion is mounted a cylindrical

brush 14 comprising bristles 15 which are set in a wooden core 16. One end of the brush has an axially extending stub shaft 17 which is journaled in a bearing 18 which is secured to the side 4 of the housing 1. The other end of the brush is provided with a square socket which is engaged by the square end 19 of a shaft 20 which is journaled in a bearing 21 in the side 3 of the housing.

A portion of the shaft 20 extends exteriorly of the housing 1 and has secured thereto a sprocket 22 which is connected by roller chain 23 to a sprocket 24 which is secured to a shaft 25.

The shaft 25 is journaled in a bearing 26 which is secured to the side 3 of the housing. The shaft 25 has a hollow portion 27 of enlarged diameter which projects interiorly of the housing and which is provided with longitudinally extending internal splines 28. The output shaft 29 of a gear box or power transmission 30 is provided with a splined portion 31 which slidably engages the connector portion 27 of shaft 25.

The transmission case 30 is secured by means of bolts 32 to the underside of the top 2 of housing 1 and its driving member has secured thereto an adapter plate 33 which in turn has rigidly secured thereto a coupling plate 34 which will be more fully described hereinafter. An opening 35 is provided in the top 2 through which the adapter plate 33 and coupling plate 34 project.

Secured to the sides 3 and 4 of the housing and extending therebetween is a nozzle body 36 having a flared opening 37 which lies closely adjacent to the brush 14 and parallel thereto. The nozzle 36 is connected to the vacuum chamber 6 by means of a hose 38 one end of which slidably connects to a fitting 39 on the nozzle and the other end of which slidably connects to a fitting 40 which is secured to the wall 9 of the partition 7. It will be understood that suitable openings are provided in the nozzle 36 and wall 9 in alignment with fittings 39 and 40 so that the nozzle communicates with the chamber 6.

Secured between the sides 41 of the nozzle 36 so as to be centrally positioned in the opening 37 thereof is a stripper or comb 43 which comprises a body portion 44 which extends parallel to the brush 14 and in which are mounted teeth or pins 45 which project from the body 44 so as to diametrically intercept the bristles 15 of the brush 14.

Power means for actuating the brushing mechanism is provided by a scrubbing machine S which may be of the type disclosed in my United States Patent No. 2,217,617, granted October 8, 1940. Such scrubbing machines are powered by an electric motor which serves to rotate a circular brush in a horizontal plane, as described in detail in said patent. The scrubbing brush is releasably secured to the motor driven spindle by means of a bayonet type of joint.

In Fig. 1 of the drawings I have shown the manner in which the machine S is utilized to drive the nap raising apparatus. The rotating spindle 46 of the scrubbing machine S has secured thereto for rotation therewith a connector plate 47 which has three circumferentially spaced lugs or dogs 48 extending radially outwardly therefrom. The dogs 48 are adapted to pass through recesses 49 which extend radially outwardly from a central opening 50 provided in the coupling plate 34, heretofore mentioned. The coupling plate has three circumferentially spaced legs 51 depending from its under surface adjacent the opening 50, each leg being intermediate two of

the recesses 49. The legs 51 rest upon and are secured to the adapter plate 33 which, as heretofore stated, connects with the transmission train 30.

When the connector 47 is engaged with the coupling plate 34, the dogs 48 abut the legs 51 thereby driving the coupling plate 34. The rotation of the coupling plate is transmitted through the gear box 30 to the sprocket 24 through the shafts 29 and 25, the gear box 30 serving to change the axis of rotation from the vertical to the horizontal.

The brush 14 is thereby caused to rotate at a suitable rate of speed, its direction of rotation being controlled by a shift lever 52 which is connected to the shaft 29 so as to move it axially whereby to engage a reversing gear as is well known in the art. The splined connection between shaft 29 and shaft extension 27 of shaft 25 permits sliding movement of shaft 29 in response to movement of shift lever 52.

The brush 14 is so mounted that the bristles 15 extend beyond the forward edges 53 of the sides 3, 4 of the housing 1, and also extend well below the bottom edge 54 of said sides. This positioning of the brush allows the brush to be brought fairly close to walls or baseboards when the carpeting covers the floor completely from wall to wall of a room.

In order to minimize the escape of dust or fibers from the apparatus, a skirt 55 of rubber or the like is secured to the sides 3 and 4 near the bottom edge 54 thereof. Further, the front end of the housing 1 is closed by a plate 56 which is flanged as at 57 and which is pivotally secured to the sides of the housing so that it rests of its own weight upon the brush 14. The plate 56 is also provided with skirt 55. For clarity of illustration, the skirt 55 is not shown in Fig. 2 of the drawings.

In order to allow the apparatus to be moved easily over the rug surface, two swivel casters 58 are secured to the bottom 8 of partition 7. Additionally, two transversely spaced rollers 59 which are rotatably mounted on an axle 60 are provided about midway between the brush 14 and the casters 58. The ends of the axle 60 are rigidly secured in arms 61 which in turn are rigidly secured to stub shafts 62 which are journaled in bearings 63 in the sides 3 and 4 of the housing. One of the shafts 62 has an extension 64 on which is secured a lever 65 which is provided with a spring-pressed knob 66 which is movable to bring a pin or dowel portion 67 thereof into or out of contact with the side 4. An arcuate row of circular cavities 68 are provided in the side 4 in the path of movement of the dowel 67 so that the lever 65 may be locked in any selected position. It will be apparent that manipulation of the lever 65 will cause the axle 60 to pivot about the axis defined by shafts 62 and thus raise or lower the rollers 59 relatively to floor level. Thereby the effective height of the brush 14 is adjusted so as to give satisfactory results on any thickness of carpet.

In operating the apparatus, the scrubbing brush, which is normally connected to the scrubbing machine S, is removed therefrom, and the scrubbing machine is placed on top of the housing 1 and connected to the coupling plate 34 by means of the connector plate 47.

The dome-shaped casing of the scrubbing machine serves to enclose the connection between the machine and coupling plate 34 and thus safe-

guards the connection against injury as well as preventing the operator from being accidentally injured by the rapidly-rotating parts. The dome-shaped casing also serves as a shield against dirt, liquids, or falling objects which might possibly injure the connecting parts if they were exposed.

The motor of the scrubbing machine is then started and the blower 11 is likewise actuated. With the brush 14 revolving clockwise, as viewed in Fig. 1, the apparatus tends to move forwardly and is merely guided in that direction by the operator. The movement of the brush raises the nap or pile of the carpet and restores it substantially to its original appearance. Fibers which are picked up by the revolving brush, are stripped from the brush by the teeth 45 of the comb 43 and are drawn by the blower 11 through nozzle 36 into chamber 6 where they collect on the exterior of the bag or filter 13.

When the forward movement of the apparatus brings it up against a wall of the room, the shift lever 52 is manipulated to cause a reversal of rotation of the brush 14 and the apparatus accordingly moves rearwardly and can be guided over another area of carpet. Thus it is not necessary to swing the apparatus around to change its direction of travel.

The skirt 55 maintains any dust and fibers within the housing and thereby prevents their escape into the room proper.

The adjustable rollers 59 can be locked at the selected position which will bring the brush into proper relationship with the pile fabric which is being renovated.

Thus it will be apparent that I have provided a light-weight portable apparatus which, in combination with a scrubbing machine can be utilized to raise the nap of carpets and pile fabrics before a cleaning operation while simultaneously raising and partially removing ingrained dirt. The apparatus is likewise used after completion of the scrubbing operation to raise the nap which may have become flattened or matted as a consequence of the cleaning and scrubbing operation.

It is to be understood that the form of my invention, herewith shown and described, is to be taken as a preferred example of the same, and that various changes in the shape, size and arrangement of parts may be resorted to, without departing from the spirit of my invention or the scope of the subjoined claims.

Having thus described my invention, I claim:

1. The combination of a nap-raising attachment for carpet cleaning machines and an operating mechanism therefor; said operating mechanism consisting of a housing, an operating handle provided on said housing, an electrical motor mounted within said housing, a vertical spindle extending from said motor, and a connector plate secured to said spindle for rotation in a horizontal plane, said connector plate being adapted to operatively engage a rotary carpet cleaning element; and said nap-raising attachment comprising a housing, a brush supported in said housing for rotation about an axis at right angles to the axis of rotation of said motor spindle, a gear box secured to said housing and operatively connected to said brush, and a coupling plate operatively secured to said gear box; said coupling plate being releasably secured to said connector plate to transmit rotary movement from said motor to said gear box, and said operating mechanism being supported above ground

level by the housing of said nap-raising attachment.

2. A combination as defined in claim 1 in which said housing of said nap-raising attachment is provided with ground-engaging wheels.

3. A combination as defined in claim 1 in which an exhaust blower is provided in said housing of said nap-raising attachment.

4. The combination of a nap-raising attachment for carpet cleaning machines and an operating mechanism therefor; said operating mechanism consisting of a housing, a push handle provided on said housing, an electrical motor mounted within said housing, a spindle extending vertically from said motor, and a connector plate secured to said spindle for rotation in a horizontal plane, said connector plate being adapted to operatively engage a rotary carpet cleaning element; and said nap-raising attachment comprising a housing, a brush supported in

said housing for rotation about an axis at right angles to the axis of rotation of said motor spindle, a gear box secured to said housing and operatively connected to said brush, and a coupling plate operatively secured to said gear box and projecting exteriorly of said housing; said coupling plate projecting into the housing of said operating mechanism and being slidably and releasably secured to said connector plate, and said operating mechanism housing being supported above ground level by the housing of said nap-raising attachment.

5. The combination of a nap-raising attachment for carpet cleaning machines and an operating mechanism therefor; said operating mechanism consisting of a housing, an operating handle provided on said housing, an electrical motor mounted within said housing, a vertical spindle extending from said motor, and a connector plate secured to said spindle for rotation in a horizontal plane, said connector plate being adapted to operatively engage a rotary carpet cleaning element; and said nap-raising attachment comprising a housing, a brush supported in said housing for rotation about an axis at right angles to the axis of rotation of said motor spindle, a gear box secured to said housing and operatively connected to said brush, a coupling plate operatively secured to said gear box, said coupling plate being releasably secured to said connector plate to transmit rotary movement from said motor to said gear box, and ground-engaging wheels adjustably mounted on said attachment housing for movement in a vertical plane, and said operating mechanism being supported above ground level by the housing of said nap-raising attachment.

6. The combination of a nap-raising attachment for carpet cleaning machines and an operating mechanism therefor; said operating mechanism consisting of a housing, an operating handle provided on said housing, an electrical motor mounted within said housing, a vertical spindle extending from said motor, and a connector plate secured to said spindle for rotation in a horizontal plane, said connector plate being adapted to operatively engage a rotary carpet cleaning element; and said nap-raising attachment comprising a housing, a brush supported in said housing for rotation about an axis at right angles to the axis of rotation of said motor spindle, a gear box secured to said housing and operatively connected to said brush, a coupling plate operatively connected to said gear box, said coupling plate being releasably secured to said connector plate to transmit rotary movement

from said motor to said gear box, and means mounted on said housing adjacent said brush for cleaning said brush in response to rotation thereof, and said operating mechanism being supported above ground level by the housing of said nap-raising attachment.

JOSEPH D. CONWAY.
